CLAIM

We claim the ornamental design for a light, as shown and
described.

DESCRIPTION

FIG. 1 is a Perspective view of a light showing our new
design;

FIG. 2 is another perspective view of the light as shown in
FIG. 1;

FIG. 3 is a Front view of the light as shown in FIG. 1;

FIG. 4 is a Back view of the light as shown in FIG. 1;

FIG. 5 is a Right-side view of the light as shown in FIG. 1;

FIG. 6 is a Left-side view of the light as shown in FIG. 1;

FIG. 7 is a Top view of the light as shown in FIG. 1; and,

FIG. 8 is a Bottom view of the light as shown in FIG. 1.

1 Claim, 6 Drawing Sheets
